UNITED STATES PATENT OFFICE.

WILLIS A. KING, OF PITTSBURG, GEORGIA.

SHOE POLISHING AND CLEANING MACHINE.

1,032,067.

Specification of Letters Patent.

Patented July 9, 1912.

Application filed December 16, 1911. Serial No. 666,169.

To all whom it may concern:

Be it known that I, WILLIS A. KING, a citizen of the United States, residing at Pittsburg, in the county of Walker and 5 State of Georgia, have invented certain new and useful Improvements in Shoe Polishing and Cleaning Machines, of which the following is a specification, reference being had to the accompanying drawings.

10 This invention relates to new and useful improvements in shoe cleaning and polishing machines and more particularly to an electrically operated machine of this character and my object is to provide a machine 15 of this character which is simple in construction and thoroughly efficient and useful in operation.

A further object of the invention resides in providing a machine formed in two sections, one section of which is adapted for 20 the application of the polish to the boot or shoe while the other is adapted for the drying of the polish upon the shoe and the final cleaning thereof.

25 A still further object of the invention resides in the provision of a revolving brush which is adapted to apply a liquid polish as the same contacts with the shoe and a further object resides in providing means 30 for the rotation of the brush in a path around the stand adapted to receive the shoe thereon.

Another object of the invention resides in providing a flexible shaft which carries the 35 polishing brush and a further object resides in providing a cam slot through which said flexible shaft extends whereby when said brush is rotated in the path about the shoe stand said brush will travel in a path de- 40 termined by the contour of the slot.

A still further object resides in providing a device which may be inexpensively manufactured and one which will thoroughly and efficiently carry out the purposes for which 45 it is designed.

With these and other objects in view my invention consists in the novel features of construction, combination and arrangement of parts as will be hereinafter referred to 50 and more particularly pointed out in the specification and claims.

In the accompanying drawings forming a part of this application Figure 1 is a longitudinal section through the machine; Fig. 55 2 is a transverse section therethrough; Fig. 3 is a top plan view of the machine; and,

Fig. 4 is an enlarged vertical section through a portion of the device showing the clutch mechanism in detail.

In carrying out my invention I shall refer 60 to the drawings in which similar reference characters designate corresponding parts throughout the several views and in which 1 indicates a housing or frame within or upon the base of which are mounted the 65 vertical posts or standards 2 and 3 which posts are mounted on the bases 4 and 5 respectively and spaced a short distance apart and encircling these posts, which are substantially circular in cross section, are the 70 hollow shafts or sleeves 6 and 7 respectively. These sleeves 6 and 7 are respectively held in position by means of the sleeves 8 and 9 which are stationary on the 75 arms 10 and 11, respectively, which are in turn respectively carried by the bases 4 and 5 and the sleeve 8 has rigidly mounted thereon a medium sized gear 12 while the sleeve 9 carries thereon an enlarged gear 13, the purposes of which will be hereinafter 80 more particularly described. The posts or standards 2 and 3 have respectively mounted thereon the bowl shaped head members or the like, 14 and 15 within which members are disposed the shoe or boot stands 16 and 85 17, said heads being respectively provided with the cam slots 18 and 19, the purposes of which will also hereinafter be described and the sleeves 6 and 7 on said posts are 90 designed for rotation thereon by being each provided with an ordinary clutch pulley 20 connected by means of the belts 21 to a motor 22 of the usual or any desired character. The sleeves 6 and 7 have provided on the upper ends thereof, immediately below the heads 14 and 15 the head members 95 23 having arms 24 thereon, and each of the latter is provided with a slot or groove 25 which receives therethrough the arms 26 and 27. These arms are formed of telescoping members the inner ends of the inner sections of which are pivotally connected to the studs 28 and 29, respectively, carried on the sleeves 6 and 7 and the outer ends of the outer sections of said telescoping arms have pivotally connected thereto the bearing members 30 and 31 through which respectively extend the flexible shafts 32 and 33. These shafts 32 and 33 are rotatably mounted in the bearings 30 and 31 and extend respectively through additional bearings 34 and 35 extended from the respective 100 105 110

sleeves 6 and 7 and in which they are also rotatably mounted and the free and lower ends of said shafts have mounted thereon the small pinions 36 and 37 which mesh respectively with the gears 12 and 13, whereby it will be seen that as said pinions 36 and 37 are rotated, the shafts 32 and 33 will likewise be rotated in their respective bearings. The opposite ends of said shafts 32 and 33 extend respectively through the cam slots 18 and 19 of the heads 14 and 15 and have mounted thereon the brushes 38 and 39 respectively which are disposed in the bowl shaped heads 14 and 15. From this construction it will be seen that as the sleeves 6 and 7 are rotated, the brushes 38 and 39 will be correspondingly revolved and their paths determined by the slots 18 and 19 around the stands 16 and 17 and said brushes will simultaneously be rotated through the rotation of the flexible shafts 32 and 33 so that when boots or shoes are placed on the stands 16 and 17, said brushes will contact with the same and remove all dirt therefrom as the brushes are revolved and rotated.

It will be seen that the brush 39 will be revolved with considerably more speed than the brush 38, in view of the enlarged gear 13 and attention must be called to the fact that a specific purpose characterizes this construction. In this connection it must be stated that the brush 39 is of the usual type used for revoluble purposes but the brush 38 has a hollow core 40 in which is adapted to be carried a liquid polish of any desired character. This polish is adapted to be entered in the core in that end thereof upon which there is a removable closure 41 and the liquid is adapted to flow to the bristles of the brush through openings 42 in the core, which openings may be closed by any desired means (not shown). It is obvious therefore, that this brush is for the purpose of applying the polish to the shoe and when an application of polish has been thoroughly made to the shoe, the same is removed from the stand 16 and placed on the stand 17 whereupon said polish may be caused to dry on the shoe and the shoe given the final cleaning by the brush 39.

In order to prevent the brushes from being in constant view of the one having his shoes cleaned, and further to prevent the splashing of the liquid polish from the brush 38 when the same is revolved, the head members 14 and 15 are each provided with an overhanging projection 43 which extends around the full path of the brushes.

As stated above, the pulleys 20 are clutch pulleys, each being provided with a conical clutch face 44 and loosely mounted on the respective sleeve portions 6 and 7, whereby it will be appreciated that said pulleys may be in constant rotation through the rotation

of the member 22 without affecting the sleeves 6 and 7, and the opposed portions 45 of the clutches are keyed, as shown at 46, to the respective sleeves 6 and 7 and are adapted for vertical movement thereon by 70 means of the yokes 47, one end of each of which is pivoted to a lug 48 carried on each of the base portions 4 and 5, while the opposite end of each of said yokes is engaged with an arm 49. Each of these latter arms 75 extends through its respective base portion and connects with one end of a rocking arm 50, while the opposite end of said rocking arm is pivotally engaged with a vertical rod or shaft 51 which extends through each of 80 the standards 2 and 3 and connects with the foot stands 16 and 17. From this construction, it will be seen that as soon as pressure has been placed on the foot stands 16 and 17 by the placing of the feet thereon, the 85 clutch mechanisms will be thrown into effective position to cause the sleeve members 6 and 7 to be rotated with the clutch pulleys 20.

In practice, one foot with the shoe thereon 90 is first placed on the stand 16, such pressure being exerted as will cause the sleeve 6 to be rotated, whereupon the brush 38 rotating about the shoe and simultaneously revolving on its axis, will thoroughly cover the 95 shoe with a polish. When it is thought that sufficient polish has been obtained, the pressure upon the stand 16 is released which will discontinue the rotation of the sleeve 6 and its adjunctive parts, whereupon the foot is 100 removed and placed on the stand 17. Pressure upon this latter stand will, as in the other instance, cause the sleeve 7 to be rotated which will cause the brush 39 to rotate about the shoe and simultaneously revolve 105 on its axis, which action will dry the polish on said shoe and finally clean the same to a high state of efficiency. When one shoe has been thoroughly polished and cleaned, the other shoe may be so polished and cleaned in 110 the manner described above.

It will be appreciated that since the pulleys 20 are loosely mounted on their respective sleeves, the machines will not normally be in operation, and in view of the clutch mechanisms which are operated by the foot stands, it will also be appreciated that either one or the other portion of the machine may be in operation while the other is idle. The motor may be in constant operation, but as 120 no appreciable amount of noise results therefrom, it will be seen that a great amount of expense and noise which is experienced in machines of this character in present use, will be eliminated.

From the foregoing, it will be seen that I have provided simple, inexpensive and efficient means for accomplishing the objects of the invention, but while the elements herein shown and described are well adapted to 125

perform the functions set forth, it is obvious that various changes in form, proportion and in the minor details of construction may be resorted to without departing from the spirit 5 or sacrificing any of the principles of the invention.

What I claim is:

1. In a machine of the class described, the combination with a foot-rest a plate provided with a guide slot surrounding said foot-rest, and a vertical post supporting the plate; of a sleeve revolvably mounted on said post, means to rotate said sleeve, a brush indirectly carried by the sleeve to revolve 15 about said foot-rest as said sleeve revolves, and a flexible shaft to which said brush is connected, said shaft being rotated from the rotation of said sleeve, and extending through the slot in said plate whereby said 20 brush will be conducted in a predetermined path about the foot-rest.

2. In a machine of the class described, the combination with a foot-rest, a plate pro-

vided with a guide slot surrounding said foot rest, and a vertical supporting post for 25 the plate; of a sleeve loosely mounted on said post, means for the rotation of said sleeve on said post, an extension arm carried on the sleeve, a guiding means for said arm, a flexible shaft carried by the free end of said 30 arm, and extending through the slot in said plate means for the rotation of said flexible shaft upon the rotation of the sleeve on the post, and a brush carried on the free end of said flexible shaft and disposed immediately adjacent said foot-rest, whereby said brush will be guided in a predetermined 35 path as the same revolves about the foot-rest.

In testimony whereof I hereunto affix my 40 signature in the presence of two witnesses.

WILLIS A. KING.
